UNITED STATES PATENT OFFICE.

IRVING E. WADE, OF GRAVITY, IOWA.

KEY-GUIDE.

1,105,472.

Specification of Letters Patent.

Patented July 28, 1914.

Application filed October 7, 1913. Serial No. 793,825.

To all whom it may concern:

Be it known that I, IRVING E. WADE, a citizen of the United States, residing at Gravity, in the county of Taylor and State 5 of Iowa, have invented certain new and useful Improvements in Key-Guides; and I do hereby declare the following to be a full, clear, and exact description of the invention, such as will enable others skilled in the art 10 to which it appertains to make and use the same.

This invention relates to new and useful improvements in key guides and has for its object the provision of a device which is 15 adapted to be arranged upon a door to facilitate in the locating of the key-hole.

Another object of my invention is the provision of such a device which may be stamped out of a single piece of material 20 and which will eliminate the use of angular extensions or projections which would result in unnecessary waste in the manufacture of such devices.

With the above and other objects in view 25 I now proceed to describe my invention in the following specification and accompanying drawings, in which,

Figure 1 is a front view of an escutcheon showing my improved key guide in place, 30 Fig. 2 is a side view of my improved key guide, and Fig. 3 is a perspective view of my improved key guide.

Reference being had more particularly to the drawings 1 indicates an ordinary escutcheon which is secured to the door by 35 any suitable means. The usual knob 2 is shown adjacent the upper extremity thereof and a key-hole is indicated by the numeral 3.

My improved key guide preferably comprises the U-shaped member indicated generally by the numeral 4, the arms of which are flared as shown at 5, and terminate in the screw receiving portions 6. The bight portion 7 of the U-shaped member is adapted 45 to lie in close proximity to the enlarged portion of the key-hole and form an abutment

for the key when the same is being inserted therein. These arms 5 are bent as shown at 8 to form the rearwardly extending portions as clearly illustrated in Fig. 3, and 50 are again bent to form the screw receiving portions 6 which are provided with the apertures 9 through which the screws 10 are adapted to extend.

It will be clearly seen from the foregoing 55 that when it is desired to make use of my improved device the same is placed on the door in such a position that the bight portion of the U-shape member will come in direct alinement with the enlarged portion 60 of the key-hole and thus the upward movement of a key which may be inserted in the lock will be limited. When such limitation of the movement has been accomplished the operator will note that the key may be 65 thrust into the key receiving aperture and the lock released.

While in the foregoing I have shown and described the preferred embodiment of my invention I wish it to be understood that I 70 may change the specific arrangement and combination of parts without in any way departing from the spirit and scope of my invention as defined in the appended claim.

What I claim is:—

A keyhole guide comprising a U-shaped member, angular extensions formed integral with the free end of the arms of the U-shaped member, the free ends of the extensions being bent back upon themselves to 80 form rearward projections, and lateral extensions formed on the rearward projections and provided with apertures for the reception of screws whereby the device may be firmly held in place.

In testimony whereof I affix my signature in presence of two witnesses.

IRVING E. WADE.
